UNITED STATES PATENT OFFICE.

WALLACE A. SCHALL, OF CLINTON, IOWA.

DESIGN FOR A CHOCOLATE-DROP CONFECTION.

Application filed April 26, 1922. Serial No. 1,966. Term of patent 14 years.

To all whom it may concern:

Be it known that I, WALLACE A. SCHALL, a citizen of the United States, residing in the city of Clinton, county of Clinton, State of Iowa, have invented a new, original, and ornamental Design for Chocolate-Drop Confections, of which the following is a specification, reference being had to the accompanying drawing, forming a part thereof.

Figure 1 of the drawings is a plan of a chocolate drop in which the design is embodied; Fig. 2 is a side view of the same.

The body portion of the cone shaped confection is ornamented with a series of elevated spiral ribs which merge at a common point at the top of the cone.

I claim:

The ornamental design for a chocolate drop confection, as shown.

WALLACE A. SCHALL.
